US0D1105914S

(12) **United States Design Patent** (10) Patent No.: **US D1,105,914 S**
(45) Date of Patent: ** Dec. 16, 2025

(54) **CONTAINER**

(71) Applicant: **RING CONTAINER TECHNOLOGIES, LLC**, Oakland, TN (US)

(72) Inventors: **Douglas Miles Dygert**, Olive Branch, MS (US); **Trevell A. Terry**, Southaven, MS (US); **Paul Vincent Kelley**, Arlington, TN (US)

(73) Assignee: **Ring Container Technologies, LLC**, Oakland, TN (US)

(**) Term: **15 Years**

(21) Appl. No.: **29/911,369**

(22) Filed: **Sep. 1, 2023**

(51) LOC (15) Cl. **09-01**

(52) U.S. Cl.

USPC **D9/523**; D9/560

(58) **Field of Classification Search**

(57) **CLAIM**

The ornamental design for a container as shown and described.

DESCRIPTION

FIG. 1 is an isometric view of a container;

FIG. 2 is an isometric view of the container;

FIG. 3 is a front view of the container;

FIG. 4 is a side view of the container;

FIG. 5 is a rear view of the container;

FIG. 6 is a side view of the container;

FIG. 7 is a top view of the container; and,

FIG. 8 is a bottom view of the container.

The broken lines are for the purpose of illustrating structure and form no part of the claimed design.

1 Claim, 8 Drawing Sheets
